CLAIM

The ornamental design for a power connector, as shown and described.

DESCRIPTION

FIG. 1 is a perspective view of a power connector showing our new design;

FIG. 2 is a front view thereof;

FIG. 3 is a rear view thereof;

FIG. 4 is a side view thereof;

FIG. 5 is another side view thereof;

FIG. 6 is a top view thereof;

FIG. 7 is a bottom view thereof; and,

FIG. 8 is an exploded perspective view of the power connector of FIGS. 1-7 shown in a typical usage environment.

The broken lines in the Figures are for environmental purposes only and form no part of the claimed design.
